US00D880506S

(12) **United States Design Patent** (10) **Patent No.:** **US D880,506 S**
Watson et al. (45) **Date of Patent:** **** Apr. 7, 2020**

(54) **DISPLAY SCREEN WITH USER INTERFACE FOR CULTURE ANALYTICS**

(71) Applicant: **Humantelligence Inc.**, Miami Beach, FL (US)

(72) Inventors: **Russell J. Watson**, New Berlin, WI (US); **Daniel Valencia**, Medellin (CO); **Victor Cortes**, Neiva (CO); **Vladimir Vivas**, Barranquilla (CO)

(73) Assignee: **HUMANTELLIGENCE INC.**, Miami Beach, FL (US)

(**) Term: **15 Years**

(21) Appl. No.: **29/624,840**

(22) Filed: **Nov. 3, 2017**

(51) **LOC (12) Cl.** **14-04**
(52) **U.S. Cl.**
USPC **D14/486**

(58) **Field of Classification Search**

(57) **CLAIM**

The ornamental design for a display screen with user interface for culture analytics, as shown and described.

DESCRIPTION

The sole FIGURE is a front view of our design for a display screen with user interface for culture analytics.

The longer broken line showing of a display screen around the periphery of the design, the shorter broken lines surrounding text, symbols, and icons, and the broken line showing of text, symbols, and icons are included for the purpose of illustrating portions of the article and form no part of the claimed design.

1 Claim, 1 Drawing Sheet
